VALVE FOR INTERNAL COMBUSTION ENGINES

Albert Frank Faber, Jr., Brooklyn, N. Y.

Application September 25, 1934, Serial No. 745,395

14 Claims. (Cl. 123—188)

This invention relates to internal combustion engines, and more particularly to the intake valves of such engines, through which the combustible mixture is taken into the cylinders.

5 An object of the invention is the provision of an intake passage of novel form whereby the various resistances to the inflow of the combustible mixture, inherent in existing types of intake passages, are minimized or eliminated.

10 Another object of the invention is the provision of means whereby the combustible mixture is introduced into the cylinder in such a manner as to promote uniform and rapid distribution thereof throughout the cylinder.

15 A further object is the provision of means whereby a maximum volume of combustible mixture may be supplied to the cylinder for any given valve opening and difference in pressures. This feature of the present invention is especially important in that it permits the use of a smaller valve opening and/or a shorter valve stroke, thus permitting the development of higher compression ratios than would otherwise be possible.

These and other objects, features and advantages will appear from the description which follows, together with the accompanying drawings, in which:

25 Fig. 1 is a vertical section of the top portion of a cylinder provided with the valve of the present invention;

30 Fig. 2 is a fragmentary longitudinal section on line 2—2 of Fig. 1;

Fig. 3 is a fragmentary longitudinal section on line 3—3 of Fig. 1; and

35 Fig. 4 is a transverse section on line 4—4 of Fig. 1.

Although the valve of the present invention is adaptable to various types of internal combustion engines, it is illustrated as applied to an aircraft 40 engine of the radial type, and it is especially suited to aircraft engines because of the necessity, in designing such engines, of securing the maximum power per unit of weight of materials used, which in turn makes it desirable to provide for the induction of the maximum volume 45 of combustible mixture into the cylinders with any given valve opening and difference of pressures.

In most existing types of intake valves for 50 valve-in-head engines there are to be found three important resistances to the flow of the combustible mixture. It is a common practice to conduct the mixture along a passage, substantially at right angles to the axis of the intake port, to a point directly over the latter, where the pas-

5 sage makes a short right-angle curve to communicate with the intake port. In this design it is of course inevitable that the valve stem and valve guide extend through the intake passage directly in the path of the incoming gases. Before reaching the intake port, therefore, the mixture must overcome the retarding resistances of the aforementioned right-angle curve and the valve stem and guide. In addition, there is considerable resistance to the flow of mixture into the cylinder, due to the fact that mixture is directed downwardly against the back of the valve proper, and it is forced to rebound nearly at right-angles in order to enter the cylinder through the opening between the valve and valve seat.

10 The several resistances described above operate to diminish considerably the rate of flow of combustible mixture into the cylinder. In the valve of the present invention these resistances are substantially eliminated, so as to permit of a 15 greater flow of mixture than would otherwise be possible under like conditions of valve opening and pressure.

15 Referring to Fig. 1, the numeral 5 designates a cylinder provided with an exhaust valve assembly 6 of any suitable type and an intake valve assembly, indicated generally at 7, designed in accordance with the present invention. The intake valve assembly comprises a valve 8 provided with a stem 9, slidably mounted in a valve guide 20 25 10, a port 11 provided with a valve seat 12, and an intake passage 13 of volute form better illustrated in Fig. 2. The intake passage 13 is provided with a flange 14 at its outer end, to provide 20 for connection with the intake manifold of the 30 engine.

35 In carrying out the present invention, as in the case of intake valves generally, it is important to reduce the valve stem 9 and valve guide to the 40 minimum diameters consistent with strength requirements. However, in the present valve, the valve stem and valve guide do not extend through the intake passage 13, but the latter is curved about the valve guide, in the form of a uniformly 45 diminishing volute. The valve guide and the projecting portion of the valve stem therefore are entirely out of the path of the incoming gases, and present no resistance to their flow.

Also, since a long, gradual curve is substituted 50 for the short right angle of existing valves, the resistance due to changing the direction of flow is considerably smaller in the present design.

55 The volute intake passage 13 is substantially circular in cross-section throughout, and is tangent to the valve guide, as shown in Fig. 2, and

to the cylinder wall adjacent the intake port 11 (Figs. 1, 4). In its preferred form, the volute intake passage is designed with uniformly decreasing cross-section area, or flow area, although this practice may be modified for reasons to be disclosed. The intake passage is open to the port 11 through substantially the entire circumference of the latter, as shown in Fig. 2.

It will be apparent from the foregoing description that the gases flowing in through the passage 13 will enter the cylinder uniformly about the circumference of the port 11 and in the form of a flat cone, that is, at only a slight angle to the plane of the port. Thus, the gases do not impinge upon the back surface of the valve 8, but flow past it along lines substantially parallel therewith, thus substantially eliminating the resistance of the valve proper which exists in other types of valve.

10 The entry of the gases into the cylinder in the manner described, and as illustrated in Fig. 2, creates a swirling movement within the cylinder, aiding in the thorough distribution of the mixture within the cylinder. It has been determined by experiment with intake passages according to the present invention that, even with the valve 8 entirely removed, the gases flowing through the passage 13 and port 11 will emerge from the latter in the form of a flat, swirling cone, leaving 15 a core of undisturbed air.

20 And since the flow area of the volute intake passage decreases uniformly throughout the circumference of the port 11, it is apparent that an equal inflow of gas will take place at every point 25 on this circumference.

It may be desirable to increase or decrease the rate of inflow of gas at a particular portion of the intake port, as for instance in the case of the arrangement shown in Fig. 1, it might be 30 desired to introduce more gas on the upper side of the valve than on the lower, so as to equalize the distribution throughout the cylinder. This effect may be achieved, in designing the volute intake passage, by readjusting the flow area of the 35 intake passage at and near its smaller end. If more gas is to be put into the cylinder at the small end of the volute, this can be accomplished by increasing the rate of diminution of flow area in that portion of the volute, thus forcing more 40 gas into the cylinder at that point. If more gas is to be put into the cylinder at the large end of the volute, the small end of the volute is made larger, so as to permit a slower inflow at the small 45 end, causing a correspondingly larger inflow at 50 the large end.

The present invention may also be employed in exhaust valve applications, although the elimination of resistances is not so important in exhaust as in intake. While the present invention 55 has been described and illustrated as applied to a radial-type engine, it is readily adaptable to other types of engines, such as those commonly employed in automobiles, etc., and may have many other applications, in cases where it is desired to pass a fluid, either gaseous or liquid 60 through a valve.

The terms and expressions employed herein are used for purposes of description and not of limitation. It is recognized that many modifications of the construction disclosed may be made 65 within the scope of the present invention.

What I claim is:

1. A valve assembly for internal-combustion engines, comprising a valve, a valve guide, a port 70 providing a seat for said valve, and a volute

passage communicating with said port throughout substantially the entire circumference of said port.

2. A valve assembly for internal-combustion engines, comprising a valve, a valve guide, a port providing a seat for said valve, and a volute passage communicating with said port throughout substantially the entire circumference of said port, said passage being formed with uniformly diminishing cross-sectional area. 5

10 3. A valve assembly for internal combustion engines, comprising a valve, a valve guide, a port providing a seat for said valve, and a passage surrounding said valve guide and communicating with said port, said passage being substantially 15 circular in cross-section, each cross-section through said passage being tangent to said valve guide.

20 4. A valve assembly for internal combustion engines, comprising a valve, a valve guide, a port providing a seat for said valve, and a passage surrounding said valve guide and communicating with said port, said passage being substantially 25 circular in cross-section, each cross-section through said passage being tangent to the adjacent edge of said port.

30 5. In a valve assembly for internal-combustion engines, the combination of a gas port and a volute passage communicating therewith.

35 6. In a valve for internal-combustion engines, the combination of a gas port and a volute passage communicating therewith, said passage being formed with uniformly decreasing cross-sectional area.

40 7. In a valve for internal-combustion engines, the combination of a gas port and a passage communicating therewith, said passage being volute with respect to the extended axis of said port.

45 8. In a valve for internal-combustion engines, the combination of a gas port and a volute passage communicating therewith, the successive cross-sectional areas of said passage being such as to cause gases introduced therein to flow into said port uniformly about its circumference. 45

50 9. In a valve for internal-combustion engines, the combination of a gas port and a volute passage communicating therewith, the successive cross-sectional areas of said passage being such as to cause gases introduced therein to enter said port at predetermined rates varying about the circumference thereof.

55 10. A device for introducing a fluid into a receiver, comprising a port and a volute fluid passage surrounding said port, said fluid passage having a constricted communication with said port substantially about the entire circumference thereof.

60 11. A device as defined in claim 10, in which the passage is of circular cross-section and gradually diminishing diameter.

65 12. A device as defined in claim 10, in which the relation between the cross section of the constricted communication and the cross section of the passage is such as to give uniform delivery of the fluid throughout the extent of the constricted communication.

70 13. A device as defined in claim 10, including a valve adapted to close the port and to provide an annular inlet between said valve and said port when said valve is opened.

75 14. A device as defined in claim 10, in which the passage is of uniformly diminishing cross-section area.
